J. J. BABBITT

SAXOPHONE AND CLARINET MOUTHPIECE

Filed Sept. 5, 1922

UNITED STATES PATENT OFFICE.

JESSE J. BABBITT, OF ELKHART, INDIANA.

SAXOPHONE AND CLARINET MOUTHPIECE.

Application filed September 5, 1922. Serial No. 586,340.

To all whom it may concern:

Be it known that I, JESSE J. BABBITT, a citizen of the United States, residing at Elkhart, in the county of Elkhart and State 5 of Indiana, have invented certain new and useful Improvements in Saxophone and Clarinet Mouthpieces; and I do declare the following to be a full, clear, and exact description of the invention, such as will enable others skilled in the art to which it 10 appertains to make and use the same.

This invention relates broadly to an improved rubber mouthpiece for reed musical instruments, and it has more particular reference 15 to one which is especially, but not necessarily, designed for use on a saxophone or clarinet.

Experience with mouthpieces of this type has disclosed the fact that the web-portion 20 of the lay is subjected to severe pressure due to extreme tightening of the screws of the ligature. After considerable use, the web-portion of the lay often crushes inwardly to an extent to render the position 25 of the reed defective. It is also to be pointed out here that the continuous stream of warm air from the player's mouth has a tendency to soften the rubber, particularly the web of the lay, and the strain subjected 30 thereon by the pressure from the tight ligature warps the lay transversely.

It is the object of this invention to overcome the foregoing circumstances by bracing and reinforcing the intermediate portion 35 of the mouthpiece throughout its circumference at the particular point mentioned. Hence, even if the ligature is tightened to the greatest possible extent, the lay of the mouthpiece will not be affected. Consequently, a single mouthpiece will last a 40 life-time.

More specifically speaking, it is another object of the invention to embed a metallic reinforcing member in a hard rubber mouth- 45 piece at a point where it will brace the web- portion of the lay, the position of the reinforcing member being inward of the outer surface of the latter so as to permit resurfacing in the event that this is desired.

50 Other objects and advantages of the invention will be apparent during the course of the following description.

In the accompanying drawings forming a part of this specification and in which like

numerals are employed to designate like 55 parts throughout the same:

Figure 1 is a central longitudinal section through a conventional type of saxophone mouthpiece showing the ligature and reed in position thereon and disclosing the improved method of reinforcing the lay. 60

Figure 2 is a transverse sectional view taken on line 2—2 of Fig. 1.

Figure 3 is a detail perspective view of the preferred type of reinforcing member. 65

Figures 4, 5, 6 and 7 are views disclosing slightly modified forms of reinforcing members.

Confining attention first to Figs. 1 to 3 inclusive, it will be seen that the reference 70 character M designates a conventional type of hard rubber saxophone mouthpiece. For the purpose of illustration, I have shown a reed R held against the lay or flat lower face of the mouthpiece held by the usual ligature 75 L or reed-holder. The web-portion P of the lay of the mouthpiece is, as before intimated, subjected to severe strain and pressure when the screws of the reed-holder are tightened, and after a time it has been found that this portion of the lay is liable to be crushed or disrupted to an extent to render it defective for further use. Hence, as before stated, it is this portion of the lay of the mouthpiece that I contemplate reinforcing and bracing. 80

Although the mouthpiece could be reinforced in some other way, I prefer to employ a special reinforcing member 1 such as it clearly illustrated in Fig. 3. This member comprises a channel portion 2 and a strap 3 which is connected at its opposite ends to the intermediate portions thereof. If desired, this strap may be provided on its inner face with lugs 4. This type of 85 reinforcing member has the opposite ends of the strap soldered or otherwise secured to the channel part.

In constructing a mouthpiece of the type disclosed in Fig. 1, the rubber is packed in a mould around a steel core which forms the usual tone chamber and bore which is connected to the neck of the mouth-pipe. During this molding process, the reinforcing member 1 is embedded in the rubber 100 and the channel part is positioned in the web portion of the lay of the mouthpiece and the strap is disposed in the upper 105

solid part thereof. It may be stated here that the aforesaid lugs 4 serve to assist in anchoring the reinforcing member in place and prevent displacement during the molding process.

It is to be noted that when the mouthpiece is completed, the channel part 2 of the reinforcing member is embedded in the web-portion P of the lay at a point which will not interfere with refacing of this portion. It will be remembered that it is often desirable to vary the distance between the reed and the lay, and in order to accomplish this result, the latter must be refaced. Hence, by embedding the reinforcing member inward of the surface of the lay, this adjustment can be made without interference of the reinforcing member. It is to be further noted that not only is the web-portion of the lay reinforced, but the entire upper portion of the mouthpiece is made more rigid throughout its entire circumference and it is practically impossible to crush the mouthpiece regardless of the degree of tightening of the ligature.

While the type of reinforcing member described is preferable, it is understood that the desired result can be accomplished by employing different forms of reinforcing members, and although it is not essential to embed these members in the rubber, this method of practicing the invention is preferred. So that an idea may be obtained of different forms of reinforcing members capable of effective use, I have shown several modified types and I direct attention at this time to Fig. 4 wherein the reinforcing member 1^a comprises a channel-shaped part 2^a having a centrally disposed integral strap 3^a or band 3^a.

Coming now to Fig. 5, it will be seen that the reinforcing member 1^b comprises a metallic sleeve 5 having the upper half of its ends cut off as at 6 to provide a relatively narrow part 3^b corresponding to the aforesaid strap.

The reinforcing member disclosed in Fig. 6 and referred to by the reference character 1^c likewise comprises a metal sleeve 5^a which simply has the upper portion of one of its ends cut off as indicated at 6^a. From the foregoing, it is evident that reinforcing members of substantial tubular formation may be employed to obtain effective results. Also, I wish to disclose the fact that, as shown in Fig. 7, a reinforcing member 1^d in

the form of a coiled spring 7 may be employed, this being embedded in the central portion of the mouthpiece at the point disclosed. Although it is not essential, all of the reinforcing members will be preferably composed of brass and all of them will be such in construction as to brace and reinforce the mouthpiece throughout the entire circumference at the particular point mentioned.

It is clearly obvious from the foregoing description that the invention is not to be restricted to the embedding of the reinforcing member within the mouthpiece, for in actual practice, it may be associated therewith in some other manner.

The manner of assembling or constructing the new type of mouthpiece is now evident and the various types of reinforcing members have been clearly described. Since the advantages are clear, it is thought unnecessary to enter a more lengthy description.

Since probably the best results may be obtained with the construction and arrangement herein shown and described, this is taken as the preferred embodiment of the invention. However, I wish it to be understood that minor changes coming within the scope of the invention as claimed may be resorted to if desired.

What is claimed is:

1. A hard rubber mouthpiece for reed instruments having a reinforcing member embedded in the web-portion of its lay, said member being disposed inward of the flat undersurface to permit refacing of the lay.

2. A mouthpiece for reed musical instruments comprising a comparatively short cylindrical reinforcing member, and a hard rubber mouthpiece molded around said member and extending beyond it in opposite directions, said mouthpiece being formed with the usual air passage and flattened lay having an opening communicating with said air passage, said reinforcing member being embedded in the mouthpiece at a point between the opening in the lay and the outer end of said mouthpiece.

3. The structure set forth in claim 2, wherein said reinforcing member is disposed inward of the flat outer face of the lay to permit refacing of the latter.

In testimony whereof I have hereunto affixed my signature.

JESSE J. BABBITT.
